UNITED STATES PATENT OFFICE.

CHARLES L. HORACK, OF BROOKLYN, NEW YORK, ASSIGNOR TO RUFUS M. WILLIAMS, OF NEW YORK, N. Y.

WHEEL.

SPECIFICATION forming part of Letters Patent No. 699,756, dated May 13, 1902.

Application filed March 30, 1897. Serial No. 629,942. (No model.)

To all whom it may concern:

Be it known that I, CHARLES L. HORACK, a citizen of the United States, and a resident of Brooklyn, in the county of Kings and State of New York, have invented certain new and useful Improvements in Wheels, of which the following is a specification.

My invention refers to wheels in general, and more particularly to wheels to be used on light vehicles having to support only moderate loads, such as bicycle-wheels, and especially to their fellies, tires, and spokes and to the means for securing and adjusting said parts in proper relations to each other.

15 The objects of my invention are to properly construct fellies of light materials—such as wood, paper, or the like—and to so dispose of such materials that said fellies, while possessing sufficient strength to resist usual and even 20 abnormal strains, may nevertheless be very light in weight; also, to suitably attach the spokes to the felly and in such manner that the union of various integral portions of which said felly may consist shall be further secured and that it may be reinforced by the 25 spokes and their securing devices.

Further objects are to provide in proper relation to the felly suitable elastic cushioning devices, whereby shocks produced by the passage 30 of the wheel over obstructions may be moderated or neutralized before reaching the felly, and to protect the joints between different sections or laminae embodied in a felly against contact with moisture or other agencies adapted to injuriously affect the same.

I accomplish these and other useful objects by the means hereinafter described, and set forth more particularly in the claims.

In the accompanying drawings, forming 40 part of this specification, and wherein corresponding letters of reference throughout the different views refer to corresponding parts, Figure 1 is an elevation of a wheel constructed according to my invention, laminae comprising 45 the felly of the wheel appearing exposed in the lower left-hand quarter thereof, while the remaining figures, drawn to an enlarged scale, represent sections of fellies and connecting parts constructed according to my 50 invention. Thus Fig. 2 shows a cross-section along line 2 2 in Fig. 1; Fig. 3, a cross-section

along line 3 3 in Fig. 1; Fig. 4, a longitudinal section along line 4 4 in Fig. 2; and Fig. 5, such a section along line 5 5 in Fig. 2, where the end of a spoke is located in such plane. 55 Fig. 6 shows a cross-section of another felly and parts connecting therewith embodying some of the leading features of my invention.

In carrying out the more important parts of my invention I employ in the construction 60 of the felly laminae, preferably made of wood and so shaped and jointed together that between them there will be formed one or more spaces or chambers, which should be closed to the atmosphere, so as to exclude dirt and 65 moisture therefrom.

Referring first to Figs. 1 to 5, inclusive, F is a wheel-felly consisting of laminae (indicated by a, b, c, d, e, f, g, h, i, j, k, and l) suitably glued or cemented together. All 70 said laminae, excepting a and l, are shown to be constructed with substantially trapezoidal cross-sections, while that of lamina a is in the form of a sector and that of lamina l is U-shaped, the outer surfaces of all the laminae 75 being made curving, so as to conform with the circular or otherwise curving outline of the cross-section of the felly. It will be seen, particularly from Figs. 2 and 3, that laminae b to k, inclusive, are arranged in two groups, 80 substantially the whole of laminae b, c, d, e, and f being located on one side of a vertical plane placed centrally with reference to the outline of the cross-section of the felly and laminae g, h, i, j, and k being placed on the 85 other side, the main joints in one group sloping toward those in the other group, the interior ends of some of said laminae being, however, made to cross said plane in such manner that the end portion of one lamina 90 will be held in contact with the side of one lamina and the end surface of another one and that the joint between said two groups will cross and recross said plane, whereby interlocking of the inner ends of the laminae in 95 the two groups will be accomplished and a splitting of the felly in such plane will be guarded against. Laminae a and l being made to extend symmetrically to both sides of said central plane tend to still further unite said 100 two groups of laminae.

As I desire to avoid the use, in combination

with my fellies, of the large inflatable pneumatic tires now in common use on bicycle-wheels, I give to my felly, combined with a light elastic tire, as I propose to employ, a cross-
 5 section of such depth as will insure proper strength and rigidity, and in order to at the same time reduce the weight of the felly as far as safe and practicable I provide spaces or pockets in its interior portions where the material thus abstracted would least contribute to its strength. For this purpose I provide suitable recesses and perforations in the laminæ, depressions in laminæ *a* and *b* together forming pockets *P'*, depressions in laminæ *c* and *d* forming pockets *P²*, depressions in *e* and *f* forming pockets *P³*, depressions in laminæ *a* and *h*, together with perforations in laminæ *g*, forming pockets *P⁴*, and depressions in laminæ *i* and *k*, together with perforations in laminæ *j*, forming pockets *P⁵*.

10 *S* and *S'* are the spokes, indicated here to be made of wire. They may be connected with the hub *H* in any suitable manner, but preferably are each placed at a slight angle with the vertical central plane of the wheel, so as to have the interior ends of alternate spokes connect with opposite ends of hub *H*, thus connecting, for instance, the interior ends of spokes *S* with the right-hand end of 15 said hub and those of the alternate spokes *S'* with its left-hand end. This is the arrangement now commonly employed in bicycle-wheels. As wire spokes are not adapted to resist compression to any considerable extent, it will be seen that the weight of the rider and the vehicle where such spokes are used must principally be transferred from the hubs of the wheels through the spokes above them to the upper part of the felly and 20 from there downward along and through said felly to the point of contact with the ground, and I accordingly so connect the spokes with the felly that every spoke at the time that the hub is suspended thereon will properly 25 transfer the strain produced thereby upon the whole of the felly. For that purpose I pass the outer thickened portions of the spokes through laminæ *a* as well as through all the other laminæ placed on one side of 30 the vertical central plane only, thus passing spokes *S* through laminæ *a*, *b*, *c*, *d*, *e*, and *f* and spokes *S'* through laminæ *a*, *g*, *h*, *i*, *j*, and *k*, deflecting the outer ends of the spokes sufficiently to place the same at right angles to 35 the main joints between said laminæ. Said spokes are screw-threaded at their outer ends, where flanged nuts *N*, resting on washers *W*, engage with the same, and are also screw-threaded at *x* above the points where they 40 curve before entering the body of the felly, screw-threaded sleeves *Y*, made bell-shaped, so as to accommodate themselves to such curvature, resting on yielding or spring washers *W'*, being made to engage therewith in such 45 manner that they may be employed as set-nuts after proper tension has been imparted

to the spokes through the instrumentality of nuts *N*.

R represents a tube or packing around the portion of the spoke within the body of the felly. The same is preferably made of elastic material, such as rubber, and is employed to prevent the cutting of the laminæ by the spoke and to moderate shocks imparted to them by the latter. At the points opposite 75 where spokes *S* and *S'* penetrate laminæ *f* and *k*, respectively, the end of lamina *l* is cut out, as at *z*, to make said spokes and nuts *N* accessible.

It is important to make the body of the felly 80 solid where the spokes pass through it, as shown in Figs. 2, 4, and 5, so as to prevent springing of the laminæ where strain is so applied to them and to give to the spokes and their packings *R* a solid and continuous 85 lateral support within the body of the felly, and this will compel either total or partial interruption of the continuity of pockets *P'* *P²*, &c. Thus in Fig. 2 pockets *P'* and *P³* appear interrupted entirely where spoke *S* passes 90 through the felly, while pocket *P²* at this point appears reduced in cross-section, pockets *P'* and *P³* under these circumstances extending only within spaces between neighboring spokes *S* *S'*. Similar conditions are indicated 95 in Fig. 5 with reference to pockets *P⁴* *P⁴* and *P⁵* *P⁵*. While in the above-described figures the pockets on the two sides of the central vertical plane of the felly are shown to be of different configurations, they are intended to 100 be and are proportioned so as to have the weight of the felly or of the wheel balanced with reference thereto. Generally speaking, and particularly where the laminæ are symmetrical with reference to said plane, it will 105 be well to arrange the pockets on both sides of said plane symmetrically thereto and to the axle of the wheel as far as the location of the spokes will permit.

T is an elastic tire of U-shaped cross-section, made of rubber, leather, or similar material and having its edges inserted in suitable grooves *G* upon the outer surface of lamina *l*, whereby a pneumatic cushion is formed between these parts, while *U* represents a shoe made of rubber with roughened surfaces, leather, or similar material, having a proper outer contact-surface and so cemented or otherwise secured to the outer surfaces of tire *T* and felly *F* as to cover the former completely as well as the joints between the laminæ comprised in the latter. Thus said shoe will not only serve to reinforce the tire, but also to protect said joints and to contribute toward firmly tying together the 125 laminæ in the wheel.

In Fig. 6, *m*, *n*, *o*, *p*, and *q* are laminæ extending symmetrically to both sides of the central vertical plane of the felly *F'*. By perforating lamina *m* and grooving out the remaining laminæ pockets *P⁶*, *P⁷*, *P⁸*, and *P⁹* are formed within the felly, as shown. A metal-

lic shoe R', with suitable head at its lower end, is shown to be inserted from the outer surface of the felly in line with spoke S⁶ and to be screw-threaded at its upper end internally to engage with the screw-threaded end of said spoke and exteriorly to engage with a set-nut Y', whereby proper tension of said spoke can be effected and the laminæ will be firmly tied together. T' is a rubber or leather tire cemented to the sides of the lower laminæ and so curved and of such stiffness as to leave at all times an air space or cushion between it and lamina q' and extending over the joints between laminæ o, p, and q and having its upper ends project inward into the body of the felly. Corresponding pockets on both sides of the central vertical plane of the felly—as, for instance, P⁶ and P⁷—might be consolidated and made continuous, in which case a plug Q, made of wood, paper, rubber, or the like, should be placed in a position, as indicated in broken lines in Fig. 6, around tube R' so as to thereby properly stay laminæ m and o opposite points where spokes connect with the felly.

I do not wish to confine myself to the relative arrangements of the various parts and the details shown and described herein, as various changes and modifications may be made by those skilled in the art without departing from the spirit of my invention.

I claim as new and desire to secure by Letters Patent—

1. In a wheel, the combination with its hub and spokes, of a homogeneous felly comprising laminæ suitably joined together and provided with an interior chamber between such laminæ, and a suitable tire around such felly.

2. In a wheel, the combination with its hub and spokes, of a felly comprising laminæ suitably joined together and containing a pocket closed to the atmosphere, one of the laminæ, where it faces an adjoining lamina being provided with a depression for the purpose of forming such pocket.

3. In a wheel the combination with its hub and spokes, of a felly comprising laminæ suitably joined together and containing a pocket, one of the interior laminæ where it faces adjoining laminæ being perforated for the purpose of forming such pocket.

4. In a wheel, the combination with its hub and spokes, of a felly comprising laminæ suitably joined together and containing a pocket, one of the interior laminæ being perforated and an adjoining lamina where it faces such perforation being provided with a depression on its face, whereby such pocket is formed.

5. In a wheel, the combination with its hub and spokes, of a felly into which the spokes are inserted, a chamber being formed in the felly between two spokes and the portions of the felly adjoining said spokes and to which said chamber extends being left solid.

6. In a wheel the combination with its hub and spokes, of a felly, comprising a series of laminæ inclosing internal chambers between

interior surfaces of such laminæ and disposed symmetrically around such felly.

7. In a wheel, the combination with its hub and spokes, of a felly comprising laminæ suitably joined together, such laminæ sloping toward each other and toward the central vertical plane of the wheel and being joined together at both sides of said plane.

8. In a wheel, the combination with its hub and spokes, of a felly comprising two groups of laminæ sloping toward each other and toward the central vertical plane of the wheel and other laminæ secured to laminæ in both of said groups.

9. In a wheel, the combination with its hub and spokes, of a felly having interior pockets provided at both sides of its central vertical plane, such felly being made solid along such plane.

10. In a wheel, the combination with its hub and spokes, of a felly comprising a series of laminæ, tension-rods passing through such felly, and means for increasing the tension of such rods independent of the tension of the portions of the spokes between felly and hub.

11. In a wheel, the combination with its hub and its felly, of a spoke passing through the felly, such spoke being deflected near the point where it enters the felly and a hood enclosing portions of the spoke at both sides of the point of deflection.

12. In a wheel, the combination with its hub, of a felly comprising laminæ suitably joined together, spokes passing through the same, and tubes independent of the securing devices of the spokes placed around said spokes and extending into adjoining laminæ.

13. In a wheel, the combination with its hub, of a felly comprising laminæ suitably joined together, spokes passing through the same and elastic packings around the spokes and extending into adjoining laminæ.

14. In a wheel, the combination with its hub, of a felly hollowed out interiorly, and spokes passing through said felly, the felly being made solid where the spokes pass through the same.

15. In a wheel, the combination with its hub and spokes, of a felly, a U-shaped tire having its edges extend into the body of the felly and a shoe secured to said tire and to the outer surface of the felly.

16. In a wheel, the combination with its hub and spokes, of a felly comprising laminæ suitably joined together, and a shoe along the outer surface of the felly and extending over the joints between the laminæ and along the bearing portion of the wheel.

In testimony that I claim the foregoing as my invention I have signed my name, in presence of two witnesses, this 29th day of March, 1897.

CHARLES L. HORACK.
